UNITED STATES PATENT OFFICE.

SAUNDERS B. SOLOMON, OF ROCHESTER, NEW YORK.

COAT.

1,172,317.

Specification of Letters Patent. Patented Feb. 22, 1916.

Application filed April 28, 1915. Serial No. 24,413.

To all whom it may concern:

Be it known that I, SAUNDERS B. SOLOMON, of Rochester, in the county of Monroe and State of New York, have invented certain new and useful Improvements in Coats; and I do hereby declare the following to be a full, clear, and exact description of the same, reference being had to the accompanying drawings, forming a part of this specification, and to the reference-numerals marked thereon.

My invention relates to improvements in coats and has for its object to provide a throat protector in conjunction with the lapel of a coat or cloak.

Another object of the invention is to provide a protector which may be used as such when desired and which when not in use may readily be concealed under the lapel or body of the coat adjacent to the lapel.

A further object of the invention is to provide a throat protector in conjunction with the lapel of a coat and as a continuation of the latter and adapted to be folded thereunder with means for holding the protector in a concealed position.

To these and other ends the invention consists in certain improvements and combinations of parts all as will be hereinafter more fully described, the novel features being pointed out in the claim at the end of the specification.

In the drawings: Figure 1 is a front view of a coat in an open position with the lapels and collar thereof unfolded to expose the throat protecting members and showing the manner of securing the same to the lining of the coat; Fig. 2 is a front view of a coat as the same would appear with my improved throat protector in concealed position; Fig. 3 is a front view of the coat shown in Fig. 2 when the protector has been unfolded and placed in an upstanding and protecting position; Fig. 4 is a sectional view taken on line $a-a$ of Fig. 1, and Fig. 5 is a sectional view taken on line $b-b$ of Fig. 3 showing the manner of fastening the throat protecting flaps when the same are in the position shown in said figure.

Similar reference numerals throughout the several figures indicate corresponding parts.

In the present embodiment of the invention I provide a coat having a collar 1, lapels 2, body portion 3 and lining 4. In connection with the lapel 2 and preferably inte-

gral therewith I provide throat and chest protecting flaps 5 and 6. The flap 6 is provided with a fly 7 Fig. 5 having buttonholes 8 adapted to be concealed under the flap 6 and to receive and engage buttons 9 positioned on the flap 5 when the flaps are in the position shown in Fig. 3. As a means for securing the flaps in a concealed position when not being used as protectors I employ any suitable means such as hooks 10 to fasten the flaps to the lining of the coat as shown in Fig. 1. It will be noted from the construction of the flaps as shown in Fig. 1 that they extend at the top thereof to a point adjacent the collar of the coat and are cut with respect thereto in such a way as to cause them to engage and fit the collar of a shirt in the manner shown in Fig. 3. The front edges 11 of the flaps are made long enough to extend, when positioned in the manner shown in Fig. 3, to a point considerably below the crossing of the lapels of the coat to afford protection to that part of the chest between the lapels usually unprotected by an outer garment, the flaps being buttoned around the throat of the wearer and serving to protect both throat and chest.

In the construction of the protecting flaps I form them integral with the lapels of the coat as shown in Figs. 1, 3 and 5. As shown in Fig. 5 the lapel is formed by folding back a portion of the cloth of the body of the coat and placing thereon cloth of the same material to form the face of the lapel, as usual, and then extending this latter material back of the lapel under the body of the coat to form first, the coat facings 15 and 16 and finally, the throat protecting flaps as continuations of the latter. Thus the flaps and the coat facings necessarily lie flat in exactly the same plane, and there is consequently no localized bunching or thickening of the material along the hinged lines of the flap, as would be the case were the flap formed separately and connected to the facing by a seam. This is very important, in the case of overcoats made of heavy cloth. When there is such a seam it causes a ridge on the exterior of the coat that gets more wear than adjacent parts and causes the nap to rub off along a well defined line that soon marks the outline of what lies beneath, and is objectionable. For this same reason I prevent the edges 5^a and 6^a of the flap from protruding on the front of the coat and, in time, revealing the presence and

position of the flap by extending the facings 15 and 16 beyond the hinge or folding lines of the flap, as shown at 15^a and 16^a in Fig. 1, so that the extra thickness will be substantially continuous and press evenly against the outer cloth at the front of the coat.

In order that no seams may be exposed in fastening the throat protecting flaps to the coat, lining members 12 and 13 are positioned on the backs of the flaps as shown in Fig. 5 and are sewed to the lining 4 of the body of the coat at 14, the ends of these linings being positioned between the body 15 of the coat under the lapel and the portions 15 and 16 forming the backs of the flaps as shown at 17 in Fig. 5. It will be noted that the fly 7 is formed by the continuation of the lining 13 and connected with the fly is 20 a reinforcing member 18 fastening to another reinforcing member 19 as at 20 on the back of flap 6. The flaps as shown in Fig. 5 are adapted to fold along the line of stitching 14 when moved from the lining of 25 the coat to a position shown in Fig. 3. In

Fig. 4 is shown the position of the flap with respect to the lining of the coat when the lapel and flap are unfolded to a flat position as in the case of Fig. 1.

I claim is my invention:

In a coat, the combination with the body portion, forming the front of the coat and the under parts of the lapels, of a piece of the same cloth secured to each side of the body portion to constitute in one continuous piece the outer part of the lapel, the coat facing and, as a continuation of the latter, a free folding flap adapted to extend rearwardly and inwardly close against the body portion or forwardly and outwardly so that the flaps may jointly close the space or opening between the lapels, the facing portion of the piece being secured permanently to the body and extending inwardly beyond the fold line of the flap to lie in the same plane therewith.

SAUNDERS B. SOLOMON.
